SYSTEM AND APPARATUS FOR REEVING
COUNTERWEIGHT CABLES

Robert W. Kaltenbach, Cleveland Heights, Ohio

Application February 8, 1934, Serial No. 710,275

5 Claims. (Cl. 193—24)

This invention relates to a system of reeving for counterweight cables, and is adapted for use on car dumpers for relieving the overload or excess load on the pan, and for maintaining the counterweight ropes, or cables, under sufficient stress to keep them taut at all times. It is especially applicable for use on car dumpers that employ a pivoted pan into which the contents of a car are directed, and from which the contents flow into a chute or other means of conveyance for delivery into the hold of a vessel. The pivoted arrangement of the pan is necessary to permit a variation of the elevation and inclination of the pan to suit vessels of different size. The means for swinging the pan about its pivot usually comprises a cable, one end of which is attached to the outer end of the pan, and the other end of which is attached to an operating drum after passing through a system of sheaves at the top of the dumper frame.

The recent trend toward apparatus, which will minimize the degradation of coal while it is being handled by the dumper has resulted in numerous additions to the pan, and has increased the weight to such an extent as to require a counterweighting system that is automatic in its operation to take care of the excess or overload, and thereby to relieve the old mechanism of undue stress.

An object of the present invention therefore, is to provide a counterweighting system, which when applied to a car dumper, meets the new operating requirements of the pan, and yet maintains adequate space for the platen and associated mechanism.

My invention, in addition, contemplates a construction, which may be readily installed in existing car dumpers without necessitating expensive alterations in the construction thereof.

Referring now to the drawing, Fig. 1 is a side elevation, partly in section, of a car dumper embodying my invention; Fig. 2 is a section taken on the line 2—2 in Fig. 1, and Fig. 3 is a diagrammatic perspective view illustrating the system of reeving.

I have shown my invention in connection with a car dumper, which has a pan 10 that is pivotally connected at 11 to bearing blocks 12 that may be slidably mounted in guideways 13 that are carried by the frame. It is to be understood that there are two bearing blocks, one at each side of the pan entrance, and that the car dumper will have the usual car receiving platen and its associated mechanism (not shown). The vertical movement of the bearing blocks and there-

fore, of the pan entrance may be controlled by cables 14, which are attached to each bearing block, and which extend over sheaves 15 and 16 at the top of the frame, and thence downwardly and around a power-driven drum 17. One position of the bearing blocks is indicated in Fig. 1 by the full lines, while another position is indicated by the dotted lines 12a in the same view.

To tilt the pan about its pivot, I have shown a cable 20, one end of which is anchored, as at 21, to the outer end of the pan, and which passes over sheaves 22 and 23 adjacent the top of the frame, and thence around a power driven drum 24. One position of the pan is indicated in full lines in Fig. 1, while a different position is indicated by the broken lines 10a in the same illustration. To counterbalance the weight of the pan, I have shown a counterweight 30, which is movable vertically in a guideway 31, and which carries a sheave 32, as is shown in Figs. 1 and 2. The counterweight 30 is not intended to be effective until the pan is slightly below a horizontal position, and so without the present invention, considerable slack occurs in the counterweight cable, whenever the pan is raised above the horizontal position. It is necessary however, to swing the pan upwardly above the horizontal position to permit vessels to pass therebeneath.

The reeving of the cable, which connects the counterweight to the pan forms part of my invention, and is best illustrated in Fig. 3, which is a diagrammatic representation. From such illustration, it will be apparent that I utilize a single cable, one end of which is fixed, as at 35, to the frame, and which passes downwardly around sheave 36 on the pan, thence upwardly around sheave 37 at the top of the frame, thence across the frame and downwardly around sheave 38 from whence it passes around sheave 39, which is carried by an auxiliary counterweight 40. After passing the sheave 39, the cable extends upwardly around sheave 41 at the top of the frame, thence over sheave 42, also at the top of the frame, and downwardly around the sheave 32 on the main counterweight, thence upwardly around sheaves 43 and 44 at the top of the frame, thence downwardly and around sheave 45 on the auxiliary counterweight, and thence upwardly again around sheaves 46 and 47 at the top of the frame, thence downwardly around the sheave 48 on the pan, and thence back to a fixed point 50 on the frame. Thus, a single cable is fixed at its ends, and is looped around a main counterweight and also intermediately at spaced points around

an auxiliary counterweight. Under normal conditions, the main counterweight is not intended to function between the zones illustrated by the pan between the lines 10 and 10a. At such time, 5 the slack in the cable is taken up by the auxiliary counterweight and the weight of the pan additions is counterbalanced.

To permit adequate movement of the auxiliary counterweight, I have shown vertical guides 51, 10 which may be supported by brackets 52, which in turn, extend forwardly of the guides 31. The auxiliary counterweight sheaves 39 and 45 may then be journalled in it as is best shown in Fig. 2. In this way, the auxiliary counterweight functions 15 to take up the slack for the full range of pan movement. To cushion the blow, if any, at the upper limit of movement of the auxiliary counterweight, I have indicated a spring 55, in Fig. 5, which may be carried either by the frame, 20 or by the upper part of the auxiliary counterweight.

From the foregoing description, it will be apparent that a system of reaving embodying my invention may be readily attached to existing car dumpers without necessitating extensive changes 25 in the construction thereof, and that the pan counterweight cable is at all times maintained in taut condition. This is advantageous, for whenever the car dumper is not in use, the pan is 30 usually tilted to its extreme limit of upward movement, and at such time, the slackened cable is prevented from swinging against the superstructure.

I claim:—

35 1. In combination, a frame, a chute swivelly mounted thereon, two counterweights for the chute, a single cable connecting the chute and counterweights across the frame, the cable having its ends fixed and reeved into three loops, 40 one of the loops supporting the chute, and the

other loops supporting the respective counterweights.

2. In combination, a frame, a material conducting chute associated therewith, two counterweights, a single cable interconnecting the cable and counterweights, the cable being reeved to support the chute at two points, and one of the counterweights at one point, and the second counterweight at two points. 5

3. In combination, a frame, a chute movably mounted thereon, two counterweight guideways associated with the frame, a main counterweight slidably mounted on one of the guide ways, an auxiliary counterweight slidably mounted in the other guideway, and being disposed intermediate the main counterweight and the chute, sheaves on the counterweights, frame and chute, and a single cable connecting the counterweights and chute, and being supported intermediately by the sheaves on the frame. 10 15 20

4. In a device of the character described, the combination with a frame, of a material conducting chute swingably mounted thereon, a main counterweight for the chute, a cable connecting the counterweight to the chute, the cable having a depending loop disposed intermediate the counterweight and chute, and an auxiliary counterweight supported in the loop. 25

5. In combination, a frame, a material conducting chute supported thereby, two counterweight guideways associated with the frame, a main counterweight and an auxiliary counterweight movable within the respective guideways, a cable fixed at its ends and being reeved into five loops, two of the loops supporting the chute 30 35 adjacent the outer end thereof, two of the loops supporting the auxiliary counterweight, and the remaining loop supporting the main counterweight.

ROBERT W. KALTENBACH.
